INVENTOR.
Morris Borsodi

UNITED STATES PATENT OFFICE

2,378,973

PENCIL

Morris Borsodi, New York, N. Y.

Application January 19, 1944, Serial No. 519,079

3 Claims.

(Cl. 120—9)

This invention relates to pencils and has to do more particularly with that type wherein leads are clamped in a permanent holder which as usually constructed has a clamping member, non-removably fixed thereto, in the nature of a clamping chuck, embodying screw threaded parts cooperating with a split sleeve to clamp the lead, and such clamps are centrally disposed to clamp the lead axially of the holder. In the present invention, a removable clamping member is provided arranged to slide into the holder and the lead is clamped in an offset position with relation to the axis of the holder the latter in the form of a plain tube. And the invention further consists of the novel combination of parts preferably constructed of any suitable material such as a high grade fibre board, especially the clamping member of the device, which is arranged as a removable part that is slipped out of the holder to insert or adjust the leads therein and replaced in the holder in a most convenient manner while applying a light pressure on the clamping member to hold the adjusted position, which pressure is increased as the clamping member is inserted to the position in the tube that may vary to suit the user.

While the construction here shown is particularly intended to produce a highly efficient clamping member for pencils, the clamping member can be used for many types of small tools, such as pen points, dental tools and the like for interchangeable use in the same holder.

It is the primary object of the invention to provide a very reliable and inexpensive pencil, embodying a removable lead clamping member, wherein the lead may be adjusted to its best suited position in the clamping member before entering the same into the holder, by which through a leverage action of the clamping member a pressure is applied to the clamp by the fingers to hold the lead so clamped along the full length thereof, except the exposed writing end and the pressure increased when sliding the clamp into the holder.

A further object of the invention, by the construction herein shown, all the component parts of the device, except the lead, may be fabricated from fiber-board by use of different thicknesses of the material, the clamping member being reinforced at parts thereof by cementing two layers together, and the holder formed from a thinner sheet for rolling to form a substantially stiff tube.

A still further object of the device relates to the offset position of the lead-clamping seat with relation to the axis of the tube holder, which provides a clear view when writing.

The invention will be better understood with other objects thereof disclosed in the following description, forming a part of this specification, and the accompanying drawing, in which

Fig. 1 is a perspective view of my improved pencil.

Fig. 2 is an enlarged end view of the clamping member showing one form thereof with a lead clamped in position therein and the clamp moved into the holder.

Fig. 3 is a side view of the clamp member as seen from the right in Fig. 2, the tubular holder shown in section and partly broken away.

Fig. 4 is a detail view of a number of strips of assembled fiber-board from which the clamp is cut after having been grooved and cemented together in long strips.

Fig. 5 is a plan view of the prepared strip and showing in dotted lines how the clamp member is cut from the strip and later folded to form the clamp member.

Fig. 6 is a cross sectional view of a modified form of the clamp shown in the holder, constructed from a single sheet of fiber-board folded as shown.

Fig. 7 is a cross sectional view of a modified form of the clamp member, made from a single sheet of metal and in position in a metal tube.

Fig. 8 is a view of the clamping device in the holder and shows the position of the device when in use.

As shown my improved pencil is designed to meet the general requirements of this art, that is, to produce an inexpensive or a more elaborate article, retaining however the principal features embodied in my improved form of pencil.

Pencils are much used as an advertising medium and would be in the class of the less expensive type, that type wherein the clamp member is folded from a material such as fiber-board of suitable thickness and the tubular holder of a thinner stock that may be rolled up to form a substantial holder for this type of pencil and on the surface of which it may be printed before same is rolled to size and the end lap cemented to form the tube.

In Fig. 1, I show how the pencil will appear in any of the forms of construction herein shown.

The tube which forms the holder, indicated by 2, may be rolled from suitable paper stock or fiber board to the diameter best suited by the number of convolutions to form the thickness of the wall and the end lap, 2', cemented in any well known manner, and this end lap before the tube is rolled up may contain printed matter thereon as shown. The tubular holder 2, preferably somewhat the usual size of the standard pencil, provides a sizeable opening 3 throughout its length. The holder may, of course, be constructed of metal or a plastic material, as an integral tube.

The clamping member 4 as indicated in Figs. 2 and 3, on a larger scale, shows this member constructed of fiber-board of suitable thickness in

the form of a built-up structure joined in any desired manner to reinforce the same, consisting of a single layer in which an inverted circular bent portion 5 provides the seat 6, in which a lead will be clamped by reinforcing portions at each side of this seat by depending portions 7 of this circular part reaching downward when as shown in Figs. 2 and 3, the outer wall of the circular part of the clamp engages the inner wall of the tube at the top while the depending arms 7 reach downward to the opposite side of the tube to provide room at the ends thereof for two reinforcing members 8, which are cemented to the inner faces of the depending portions 7, to reinforce the same, and the edges 9 of the parts 8 are accurately placed to conform to the circular formation of the single layer to thereby increase this circular grip around the lead. The free ends 10 of the reinforcing members are bent to extend in opposite directions and are of a length to yieldingly engage when within the tube holder 2 about as shown, to engage the center of the tube as indicated at 11. The depending arms 7 and reinforcing members 8 thereof act like levers to close the circular part for which a space 12 between the levers is provided to grip on the lead, both when sliding the clamp member into the tube to the proper position required, and before entering the tube, the lead may be adjusted in the clamp member, and this adjustment maintained by slightly pinching the levers together and this pressure is increased by the tube, as the clamp member is gently moved therein.

Figs. 4 and 5 show how the clamping member is constructed. A strip 13 is first cut to proper width and the circular groove forming the lead seat is rolled therein, then the reinforced portions 8 which form the leverage members are cemented thereto, so the edges 9 thereof will conform to the circular seat 6. The clamping member is then ready to be trimmed on the broken lines indicated at 13, which is then folded and the trimmed edges will conform to the shape shown in Fig. 3.

In Fig. 6, I show the clamping member folded from a single sheet of film-board of suitable thickness, which is folded as shown in any well known manner in long length pieces over a folding rack, after creasing the paper on the lines as required, then trimmed to the same shape at the ends to form and length and shape.

In Fig. 7, I show the clamp member as constructed of a thin metal, which need not be reinforced, the usual practice of forming a blank of the proper shape, which is readily punched, then bending to the form shown, in bending dies. This metal type of the device, may be in the class of the more expensive type of pencil, highly finished in many different styles.

All the forms herein shown have the following advantages over the types of clamps generally used to hold and clamp the lead. In my improved clamping member one of these advantages is, the holder tube 2 is plain, no fittings of threaded parts are required of any kind, since the clamping member 4 slides into the open tube to engage the inner wall thereof and the clamp member is readily removed, and the lead is then free to be moved to a new position, since the depending lever arm swings open and by the fingers may be slightly compressed to again grip the lead, then the same is slid back into the tube to allow as much as suits the user to extend out of the tube.

Another feature of the clamp is that it grips the lead the full length within the holder and

another feature, since the lead is offset from the axis of the holder, the user has a clear view of the writing point as shown in Fig. 8.

Having described my invention, I claim:

1. In a pencil of the type described, the combination including a tubular holder, a removable lead clamping member arranged to slide into the open end of the tube holder to engage the inner wall thereof, said clamp member formed of built-up layers of fiber-board joined together to reinforce the same and to form in cross section when folded and in position in the tube for one part thereof in a single layer portion, to form a circular bend appearing in cross section of said part the full length thereof, the apex of which forms the seat in which said lead is seated, the outer part of said circular bend engaging the inner wall of the tube to be offset from the axis of the tube, downward reaching portions each side of said circular part and extending toward the opposite side of the tube, forming lever portions, said portions reinforced at the inner sides thereof for the edges to conform to said circular reinforced parts to increase said circular formation, the outer free ends of the reinforced parts bent in opposite directions for the free ends suitably bent to engage the inner wall at the sides thereof, to yieldingly close the circular part to clamp the lead, and hold the clamp member in any adjusted position thereof in the holder.

2. In a pencil device of the type described, the combination including a tubular holder, a lead clamping member arranged to slide into said holder to engage the inner wall thereof, said member formed of built-up layers of fiber-board joined together to reinforce same, to form in a single layer portion thereof as viewed in cross section when folded and in a clamped position within the tube where one part thereof, in a single layer portion, is bent to form a circular seat, the outer face of which engages the inner wall of the tube, downward extending portions of said circular layer part forming lever portions reaching downward to the opposite side of the tube, said levers reinforced on the inner sides thereof, so the edges thereof conform to said circular seat the full length of the clamping member and so retained by a closing clamping action applied by oppositely bent over-hanging portions of said reinforced parts the free ends of which engage the contour of the tube inner wall at each side to urge the lever portions together under a yielding action of both the tube and the clamp.

3. In a pencil of the type described, the combination including a tubular holder, a removable lead clamping member arranged to slide into the open end of the holder to engage the inner wall thereof, said clamp member formed of a single sheet of material of a length suitable to provide a sliding action in the holder and support the lead in a clamped position in a circular bent part to lap around the lead the greater part thereof, the outer surface of said circular part when in the holder engaging the inner wall, arms extending from said circular part forming levers separated to provide a space between the same, the free ends bent in opposite directions to yieldingly engage the inner wall of the holder at the sides opposite said circular part, whereby on entering the holder tube a pressure is applied to close said circular part to clamp the lead and hold the clamp member in any adjusted position within the holder.

MORRIS BORSODI.
